United States Patent Office

Des. 229,337

Patented Nov. 20, 1973

229,337

CURTAIN FABRIC

Peter Schroeder, Stockacker CH-8905, Arni, Switzerland

Filed Jan. 10, 1972, Ser. No. 216,881

Claims priority, application Germany July 10, 1971

Term of patent 14 years

The single figure is a plan view of a curtain fabric showing my new design, the dark background being for purposes of illustration only.

I claim:

The ornamental design for a curtain fabric, as shown and described.
